(57) **CLAIM**

The ornamental design for an electronic housing, as shown and described.

DESCRIPTION

FIG. 1 is a perspective view of an electronic housing showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the remainder of the electronic housing and the unshaded regions therein in FIGS. 1–7 is for environmental purposes only and forms no part of the claimed design. The difference in shading in FIGS. 1–7 indicates a contrast of appearance and does not depict any particular color, texture, or material.
